TUNING DEVICE

William G. Wheat, Kansas City, Mo., assignor of
one-fourth to Dwight Roberts and one-fourth
to Joseph N. Miniace, both of Kansas City, Mo.

Application February 1, 1937, Serial No. 123,317

7 Claims. (Cl. 74—10)

My invention relates to circuit tuning devices, and more particularly to means for tuning an electrical circuit, such as a radio circuit, or circuits.

5 The principal purpose of my invention is to provide a tuning device comprising one or more condensers, or similar members, made up of stationary means and movable means, the relative position of the movable means to the stationary means determining the tuning of the circuit in which said movable and stationary means are interposed, and means for adjusting said movable means relative to the stationary means, comprising weighted means, or means of relatively 10 large mass, for causing the continued movement of the movable means relative to the stationary means after such movement has been initiated by the operation of means rotating the weighted means, or member of large mass. This may be 15 referred to as a "free wheeling" tuning mechanism, in that the weighted means, or means of large mass, after being started, will continue to rotate the parts due to the inertia of the member of large mass tending to continue such rotation, 20 and because my improved apparatus comprises means, whereby, if said movable members, or movable means, associated with the stationary means to control the tuning of the circuit, or circuits, in which said movable means and stationary 25 means are interposed, reaches the limit of its movement in either direction, the rotatable means of large mass will continue its rotation without moving the movable means interposed in the circuit, thus preventing any damage to such movable means.

More particularly my invention comprises means for tuning a variable condenser, or other adjustable means, for tuning a circuit, comprising a tuning shaft associated with the rotor, or rotors, of the condensers, or similar variable means, and rotatable means that is possessed of a large amount of inertia, which is provided with means for setting the same into rotative motion, and which is provided with means connecting the same with the tuning shaft to set the tuning shaft into rotation, but at a speed of rotation that is less than the speed of rotation of the means of relatively large inertia. This is accomplished by some speed reduction driving means, a worm 40 drive being preferred, but other driving means, such as belt drives, or reduction gears of various sorts being usable.

More particularly my invention comprises such speed reduction driving means between rotatable means of high inertia, such as a rotatable member

of large mass, and a tuning shaft for a condenser, or gangs of condensers, or similar adjustable variable means for tuning a circuit, or circuits, and a spring clutch mechanism, which permits the rotation of the means of large inertia to continue, if the rotation of the tuning shaft, or the adjustable circuit tuning means associated therewith, is positively halted by some means, such as a limiting stop.

One of the principal advantages of my invention is that with a circuit tuning apparatus, such as I have provided, the dial which is usually associated with the tuning shaft, and said tuning shaft and the adjustable circuit tuning means rotating with said shaft, can be rotated much 10 more steadily than is possible by direct rotation of the ordinary tuning shaft by hand, and the rotation thereof by my improved means can be halted at a desired point by an unskilled operator much more accurately than is possible with 15 a tuning shaft that is rotated by such an unskilled operator by direct hand operated means carried by the tuning shaft itself, or by means 20 geared to the tuning shaft and rotated by the operator at a higher speed than the tuning shaft. 25 The operation of such a geared driving means, or other speed reduction means, from a hand wheel, or some other means, that is rotatable by the operator, to drive a tuning shaft, is very 30 tedious and due to the fact that the rotatable operating member has to be rotated over a considerable arc to cause any effect on the tuning, the impatience of the operator tends to eliminate 35 any advantage that is gained by the speed reduction drive between the tuning shaft and said operating means, unless my invention is applied thereto, whereby the member of relatively large mass provides an inertia device, which is readily 40 set in rotation by the operator and continues the rotation of the parts, including the drive between said rotatable operating means, or other operating means, for manual operation of the device and the tuning shaft, thus causing the operator 45 of the device to devote his attention mainly to the dial indicating the position of the movable means, such as the rotor plates of the condensers that are used for tuning the circuit, and enabling the operator to stop the rotation of the tuning shaft very accurately by merely engaging 50 his hand with the operating means to stop the rotation of the inertia means, such as a flywheel-like member of large mass, having its center of mass on its axis of rotation. Such a member 55 that has its center in mass of its axis of rotation, or substantially in its axis of rotation, will provide 60

a uniform, or substantially uniform, rotation of parts, particularly where a speed reduction drive means is provided, no matter what position of the condenser plates of the rotor, or rotors, of 5 the apparatus may have.

Other objects and advantages of my invention will appear as the description of the drawing proceeds. I desire to have it understood, however, that I do not intend to limit myself to 10 the particular details shown or described, except as defined in the claims.

In the drawing:

Fig. 1 is a fragmentary view partly in elevation and partly in section, showing my improved tuning apparatus.

Fig. 2 is a fragmentary view, similar to Fig. 1, showing a modification of my improved tuning apparatus.

Fig. 3 is a fragmentary view partly in vertical 20 section and partly in elevation of a further modification.

Fig. 4 is a section taken substantially on the line 4—4 of Fig. 1.

Fig. 5 is a fragmentary section taken substantially on the line 5—5 of Fig. 3.

Fig. 6 is an enlarged fragmentary front elevational view of the guiding means for the actuating member in Fig. 3, the actuating member and arm being omitted, and

30 Fig. 7 is a fragmentary view partly in vertical section and partly in elevation, of a further modification of my invention.

Referring in detail to the drawing, my tuning apparatus is shown as being mounted in a casing, 35 or cabinet, such as is commonly used for radio apparatus, having a bottom wall 10 and a front wall 11, a base member 12 being secured to the bottom wall 10. Said base member 12 is provided with an upstanding bracket 13 carrying a housing

40 14 constituting a shield for the stationary plates, or stator members, 15 of a plurality of condensers. A shaft 16 is mounted in the upstanding end walls 17 and 18 of the shield, or casing, 14 for rotation therein, any suitable bearings being provided for 45 said shaft. The rotor members having the plates 19 are mounted in fixed position on said shaft to rotate therewith so that said rotor plates will move into cooperative relation to the stator plates 15 to progressively vary the capacity of the condensers 50 thus formed, in a well known manner. Said condensers are interposed in electrical circuits by connection of the respective stator and rotor plates therein. Each group of stator plates 15 is, of course, insulated from the other groups in the 55 usual manner. Any suitable mounting for the stator plates may be used, such as the bar 20 extending between the end members 17 and 18, which is secured therein, and which is provided with sleeve-like insulating means 21 surrounding

60 the same to insulate the plates 15 from the bar 20. It is, of course, to be understood that the stator and rotor plates can be mounted in any desired conventional manner, as is well known, to obtain the desired relative adjustment and desired capacity relation thereof to produce the desired tuning effect on the circuits in which the same are located. The shaft 16 extends through a suitable opening in 65 the front wall 11 and any indicating means, such as a dial, 22 is provided on said shaft to indicate 70 the position of the rotor members relative to the stator members.

Mounted on the base member 12 is a frame having the transverse bottom member 23, the upstanding side members 24 and a transverse top member 25. Depending from the transverse

member 25 is a U-shaped bracket 26 having a transversely extending portion 27 carrying a ball bearing 28 for the vertically extending shaft 29. The shaft 29 also extends through an ordinary bearing 30 in the transversely extending frame 5 member 25. Secured to the end portion of the shaft 29 in any suitable manner, as by means of a set screw 31, is the hub portion 32 of a hand wheel of large diameter 33 having the knurled, or roughened, edge portion 34, the peripheral edge portion 10 34 extending through a suitable opening in the front wall 11 below any suitable shield 35 therein, so as to project from the casing, or housing, for the apparatus, so that the knurled edge, or roughened rim, of said hand wheel may be engaged by 15 the operator of the device. The wheel 33 thus constitutes a manual operating means for rotating the shaft 29, and, as will be described below, the tuning shaft 16.

Mounted on said rotatable member, or hand 20 wheel, 33 is a weight 36, which may be made in any desired manner, but must be of such size and weight that with the wheel 33, will constitute a rotating mass that is relatively large compared with the other moving parts of the apparatus, so 25 that the inertia of said mass will create a momentum for the rotatable member 33 that will cause it to rotate for a large number of turns after being given a start by engagement with the roughened operating edge portion 34 thereof by the fingers of 30 the operator of the apparatus. The weight 36 should be so proportioned and so mounted on the member 33 that said member 33 and the weight 36 will constitute a mass, the center of mass of which lies in the axis of the shaft 29, so that the rotation 35 thereof will be uniform about said axis. The weight may be detachably connected to the wheel 33 by suitable securing elements 37.

The upper end of the shaft 29 extends through the bearing 30 and has a disk 38 fixed thereto to 40 rotate therewith in any desired manner. A similar disk-like member 39 is mounted in cooperative relation thereto, being slidably mounted on a shaft 40, which is in axial alignment with the shaft 29 and which is mounted in a bearing 41 on the up- 45 standing U-shaped bracket 42 provided on the transversely extending frame member 25. A hub 43 is provided on the disk 39 and a slot 44 is provided in the shaft 40, through which the pin 45 extends, which is mounted in the hub 43, as will be 50 evident from Fig. 4. A collar 46 is fixed on the shaft 40 in any suitable manner, as by means of a set screw, and a compression coil spring 47 is mounted between the collar 46 and the hub 43, urging the disk 39 into frictional engagement with 55 the disk 38. It will be obvious that the tension of the spring 47 can be adjusted to get the desired frictional gripping action between the disks by adjustment of the collar 46 on the shaft 40.

On the upper end of the shaft 40 a worm 48 is 60 provided, said worm 48 engaging with a worm wheel 49 provided on a countershaft 50, which is mounted in a suitable bearing provided in the bracket 51 extending upwardly from the U-shaped bracket 42, and in a suitable bearing in the end 65 wall 17. Also fixed on the shaft 50 is a gear 52, which is shown as being relatively small and which meshes with a larger gear 53 fixed on the shaft 16.

It will be evident that as the operating member 34 is set into rotation by the manual movement 70 thereof, the large mass of the members 33 and 36 is set into rotation, as well as the shaft 29, and the shafts 50 and 16 through the worm drive and the gear drive above referred to. Also it will be noted that after the large mass comprising the members 75

33 and 36 is set into rotation, and the hand is disengaged from the rim 34 thereof by the operator, the mass will continue to rotate due to inertia thereof, continuing the rotation of the intermediate driving means and the shaft 16, thus continuing the rotation of the dial 22 and the rotor members having the rotor plates 19, and that said shaft 16 and the rotor plates will move at a much slower rate of rotation than the shaft 29 and the large rotating mass moving therewith comprising the members 33 and 36. As a result, all that is necessary to set the shaft 16 in operation is to give the rotatable member 33 a start, whereupon the parts will "free wheel", or coast along, for a considerable interval, enabling the operator to put his full attention on the dial indicating the position, or the adjustment of the tuning apparatus, comprising the movable rotor plates.

The member 33 can be turned at the exposed rim portion 34 thereof as frequently as may be necessary to get the rotor members in approximately the desired adjustment and then the operator can halt the movement of the shaft 16 and the rotor plates at the exact point desired by engagement of the fingers with the rim 34 of the rotatable member 33, thus stopping the rotation of the shaft 29 and, through the worm wheel and gears, the shaft 16 substantially instantaneously, the parts associated with the clutch member 38 having such a relatively small mass and so little inertia that there will be no slippage of the clutch members 38 and 39 under such circumstances. In order to prevent any play, or back lash, between the teeth of the gears utilized in the drive, the shaft 16 is provided with a coil spring 54, which is secured at one end to said shaft, and at the other end to a pin 55 on the end wall 18. Should, however, the operator rotate the member 34 continuously, or carelessly, to such an extent that he will move the rotor members to the limit of their rotation so that these rotor members will engage stops customarily provided for limiting the movement thereof at opposite ends of the arc through which the same are adapted to move, to either obtain their maximum or minimum capacity relationship to the stator plates 15, the friction clutch will operate to prevent any damage to any of the parts. That is, the shaft 16, the gears 52, 53, shaft 50 and shaft 40, and all the parts carried thereby, will stop, stopping the disk 38 from rotation, whereupon the disk 38 will turn relative to the disk 39 without causing any rotation of the disk 39 due to the yielding engagement of said disks 38 and 39 through the spring 47. Of course, the friction between the members 38 and 39 will act to some extent as a brake to reduce the amount of rotation that the member 33 will have. It is, of course, to be understood that any suitable mounting and spacing means may be provided for the parts, such as the spacing sleeve 56 between the gear 53 and the member 11 and the sleeve 57 carrying the rotor plates 19, and any suitable means for centering the rotor plates relative to the stators may be provided, such as the resilient means 58. Any suitable cover for the dial 22, such as the concavo-convex glass covering 56, may be provided, if desired.

Instead of providing the actuating means directly on the rim of the rotatable member carrying the weighted member and constituting part of the rotatable means of large mass, other actuating means may be provided, such as shown in Figs. 3 and 5. The base member 12 is provided with a bracket 60, which has a transversely extending portion 61 having an opening therein, in

which the sleeve 62 is mounted, which is provided with a groove 63, in which the yoke 64 is mounted. The yoke 64 is made of a pair of members, which are secured together by means of a transverse securing member 65 at one side thereof and by means of a member 66 at the other side thereof, which constitutes a pivot for an arm 67 extending through an opening in the front wall member 11, and which has a finger piece 68 mounted thereon, which is recessed at 69 for engagement of a finger of the operator therewith to enable the operator to push downwardly on said member 68 and at the same time move the same laterally.

A spring 70 is provided, which normally presses upwardly on the arm 67 to hold the friction block 71, fixed thereto, away from the annular rib 72 provided on the rotatable member of large mass 73, said member 73 being fixed on the shaft 29 by any suitable means, such as the set screw 74, a spacing collar 75 being provided on the shaft 29 between said member 73 and the base member 12. It will be obvious that when the member 68 is pressed downwardly and moved laterally, the friction block 71, which may be made of any desired material, such as fiber, that would have a frictional engagement with the rib 72, is engaged with said rib and the arm 67 acts to rotate the rotatable member 73 and the shaft 29, the shaft 29 being connected with the shafts 50 and 16 in the same manner as previously described. However, as soon as the operator removes the fingers from the finger piece 68 the spring 70 will act to disengage the member 71 from the rib 72, permitting continued free rotation of the member of large mass 73 and the parts connected therewith through the shaft 29.

The member 11 is provided with an upper shield, or guard, 76 and a lower shield, or guard, 77 located on opposite sides of the arm 67, these being curved, as will be obvious from Figs. 3 and 6, and provide a slot 78 between the same, in which the arm 67 operates. However, in order to prevent the engagement of the member 71 with the member 12 after said member 73 has been started by means of the finger piece 68, the upwardly directed edge portions 79 are provided on the lower shield member 77, causing the arm 67 to ride up on the cam edges 79 thus formed, which will lift the arm 67 and the member 71 off the rib 72. It is, of course, to be understood that the sleeve 62 acts as a bearing for the shaft 29, said shaft 29 being rotatable in the sleeve 62, said sleeve being fixed in the opening in the member 61, having a reduced end portion 80 extending through said opening.

While a combination worm and gear drive is shown in Fig. 1, other means for driving the tuning shaft from the rotatable means of large mass, may be provided. Thus in Fig. 2 a rotatable member of large mass 81 having its center of mass in the axis of the shaft 82, is shown, said shaft 82 being mounted in bearings on a U-shaped bracket 83 provided on the front wall member 11' and being provided with a knob 84 fixed thereto by any suitable means, such as a set screw, or pin, which is provided with a roughened, milled, or knurled, edge 85, said member 81 being fixed by a set screw, or other similar means, to the shaft 82 so that rotation of the knob will rotate the weighted wheel, or rotatable member of large mass 81. A pulley 86 is also fixed to the shaft 82 to rotate therewith in any suitable manner, as by means of a set screw 87, and a belt 88 operates over said pulley and over a pulley 89, which

is rotatably mounted on the sleeve 96, said sleeve being rotatably mounted on the shaft 16'.

A collar 90 is fixed to the sleeve 96 by means of a set screw 91 and a coil compression spring 92 engages with the hub 93 of a friction disk clutch member 94, which is slidably mounted on the sleeve 96 to rotate therewith, and which engages with a clutch face 95 provided on the pulley 89. The pulley 89 will thus normally rotate with the shaft 96 unless the shaft 96 is stopped, whereupon the pulley 89 will rotate relative to the shaft due to the provision of the resilient friction disk clutch arrangement. A gear 97 is fixed to the sleeve 96. The gear 97 meshes with the gear 99 that is mounted on the shaft 100, the gear 99 being appreciably larger than the gear 97, and a gear 101 being also provided on the shaft 100, said shaft 100 being mounted in the end wall 17 of the casing 14, or in any other desired frame member, by any suitable means, such as a nut 102 engaging a screw-threaded end on said shaft, said shaft 100 being stationary and the gears 99 and 101, which are, preferably, made integral with the sleeve portion 103 rotating on said shaft. The gear portion 101 is, preferably, in the nature of a pinion, and meshes with a gear 104 that is fixed on the shaft 16' by means of the set screw 105, or other similar means. The shaft 16' extends through the sleeve 96 and the hub of the gear 104 is spaced from the gear 96 by means of a spacing ring 98, and from the member 17 by means of a collar 106. The shaft 16' has the rotatable indicator member, or dial member, 22 provided thereon, in the same manner as previously described, while the sleeve 96 has the dial or indicator member 22' mounted thereon to rotate therewith. Thus means is provided for indicating the rotation of both the sleeve 96 and the shaft 16' in this case. In order to provide the necessary tension on the belt, an idler pulley 107 is provided, engaging the belt 88, which is mounted on an arm 108 mounted on a pivot member 109 and urged into engagement with the belt by means of the spring 110 in a well known manner.

It will be obvious that as the member 84 is engaged and twisted, or rotated, to rotate the member 81, the pulley 86 and belt 88 will rotate the pulley 89, and through the sleeve 96 and the train of gears, the shaft 16', which shaft 16' will rotate at a very slow speed as compared with the shaft 82. This will continue until the limiting means stopping the rotation of the shaft 16' is engaged in the manner previously referred to in connection with Fig. 1, whereupon the friction clutch comprising the members 94 and 95 will cause the rotation of the sleeve 96 and the shaft 16' to be halted, although the pulley 89 and the member 81 will continue to rotate due to the fact that the inertia of the mass of the member 81 will continue such rotation.

In Fig. 7 a further modification is provided. A shaft 82, which corresponds to the shaft 82 in Fig. 2, is mounted in a similar manner to that previously described, and the rotatable member of large mass 81 is fixed to said shaft 82 in a similar manner to that previously described. Also fixed on the shaft 82 to rotate therewith, is the pinion 111, which meshes with the gear 112, which also has a pinion 113, preferably, formed integral therewith, or mounted to rotate in unison therewith, which is mounted on a fixed shaft 114 secured in any suitable manner to the front wall 11', a spacing sleeve 115 being provided between said front wall and the hub of the gear 112. The

pinion 113 meshes with a gear 116, which has the friction disk 95 provided thereon, corresponding to the disk 95 shown in Fig. 2. The other parts shown in Fig. 7 are the same as previously described in connection with Fig. 2 and are correspondingly numbered, the operation being substantially the same as previously described, except that the drive from the shaft 82 to the sleeve 96 is through gearing instead of by means of a belt.

It is of course, to be understood, that in any form of the invention, the gear ratios, size of gears, size of pulleys, and so on, can be varied as may be desired to obtain the desired speed reduction between the driving, or operating, shaft and the condenser, or tuning shaft, and that this can be utilized to obtain any fineness of reading of the dial, or adjustment of the condenser, or other tuning member, that may be desired.

What I claim is:

1. An apparatus of the character described comprising a tuning shaft, stop means limiting rotation of said tuning shaft, a driving shaft, a member of large mass mounted on said driving shaft to rotate therewith substantially about its center of mass, means for rotating said member of large mass and manually controlling the amount of rotation thereof and a driving connection between said driving shaft and tuning shaft, said driving connection comprising means permitting rotation of said driving shaft by the inertia of said member of large mass upon halting the rotation of said tuning shaft by said stop means and halting rotation of said tuning shaft by said manual means acting on said member of large mass to stop said member of large mass.

2. Variable means for tuning an electric circuit, comprising stationary and movable elements interposed in said circuit, means for mounting said elements in such relation to each other that the effect of said elements on said circuit will vary in accordance with the relative position of said elements, a rotatable shaft connected with said movable element to move the same relative to said stationary element in proportion to the rotation of said shaft, and means for rotating said shaft comprising a rotatable element of large mass, a driving connection between said element of large mass and said shaft, said driving connection permitting halting of said shaft without halting said element of large mass, but halting said shaft upon halting rotation of said element of large mass, the center of mass of said rotatable element of large mass lying substantially in the axis of rotation thereof, and means for manually controlling the amount of rotation of said element of large mass.

3. An apparatus of the character described comprising driven means including a tuning shaft, driving means including a driving shaft, a member of large mass mounted on said driving shaft to rotate therewith substantially about its center of mass, means for rotating said member of large mass and manually controlling the amount of rotation thereof and a driving connection between said driving shaft and tuning shaft, said driving connection comprising yielding clutch means, and the inertia of said driving means being much greater than that of the driven means.

4. An apparatus of the character described comprising driven means including a tuning shaft, driving means including a driving shaft, a member of large mass mounted on said driv-

ing shaft to rotate therewith substantially about its center of mass, means for rotating said member of large mass and manually controlling the amount of rotation thereof and a driving connection between said driving shaft and tuning shaft, said driving connection comprising means for rotating said tuning shaft at a much slower speed than said driving shaft, and including a friction clutch having resilient means for holding said clutch in frictional engagement, the inertia of said driving means being much greater than that of the driven means.

5. Circuit tuning means comprising rotatably mounted tuning means, an indicator member indicating the position of said rotatably mounted tuning means, a manually rotatable operating member for initiating rotation of said rotatable means, and a weighted member of much greater mass than said rotatably mounted tuning means 10 directly connected with said operating member to rotate about its center of mass in unison with and at the same speed as said operating member, and extend the rotation of said rotatably mounted tuning means after release of said operating member by the operator, and a slip driving connection between said rotatably mounted tuning means and said weighted member operating to instantaneously halt the extended rotation of said tuning means upon halting rotation 15 of said operating member by manual engagement thereof by the operator upon said indicator member reaching a desired indication.

6. Circuit tuning means comprising rotatable means and stationary means having capacity relation to each other, means for indicating the position of said rotatable means, stops for limiting the rotation of said rotatable means, manual means for initiating rotation of said rotatable means, and rotatable inertia means ex-

tending the rotation of said rotatable means after manual initiation thereof, means positively connecting said manual means and said means for extending the rotation thereof and a slip driving connection between said means for extending said rotation and said rotatable means, said connecting means cooperating to halt extended rotation of said rotatable means by engagement with said manual means at any indicated position thereof and by said stops at the 10 limiting positions of said rotatable means during rotation of said inertia means.

7. Circuit tuning means comprising rotatably mounted tuning means, an indicator member rotating with said rotatably mounted tuning means, 15 stops limiting the rotation of said rotatably mounted tuning means, a manually rotatable operating member for initiating rotation of said tuning means, and a weighted member of much greater mass than said rotatably mounted tuning means directly connected with said operating member to rotate about its center of mass in unison with and at the same speed as said operating member, and extend the rotation of said rotatably mounted tuning means after disengagement of said operating member by the operator, and a slip driving connection between said weighted member and said rotatably mounted tuning means, said driving connection operating to instantaneously halt the extended rotation 20 of said tuning means upon halting rotation of said operating member under the control of the operator with said indicator member at a desired indication, and to permit rotation of said weighted means to proceed, upon limitation 25 of the rotation of said rotatably mounted tuning means by said stops.

WILLIAM G. WHEAT.
